ATTORNEY.

UNITED STATES PATENT OFFICE.

JOHN M. DEITZ, OF OTISCO, MICHIGAN.

WAGON-STAKE.

SPECIFICATION forming part of Letters Patent No. 339,976, dated April 13, 1886.

Application filed February 8, 1886. Serial No. 191,171. (No model.)

To all whom it may concern:

Be it known that I, JOHN M. DEITZ, a citizen of the United States, residing at Otisco, in the county of Ionia, State of Michigan, 5 have invented certain new and useful Improvements in Uprights for Wagons, of which the following is a specification, reference being had therein to the accompanying drawings.

My invention has relation to standards or 10 uprights for lumber and like wagons, the object being to provide a strong rigid metallic standard or upright that will not become loose or wedged out of position; and the invention consists in certain features of construction hereinafter specified, and particularly pointed out in the claims.

Referring to the drawings, Figure 1 represents a standard in side elevation constructed in accordance with my invention and mounted 20 upon the end of a bolster. Fig. 2 is a perspective of the same, and Fig. 3 is a modification, hereinafter referred to.

Like letters indicate like parts in all the figures of the drawings.

25 A represents a portion of a bolster of a lumber-wagon, upon which is mounted my improved standard B. The standard B is made of bar-iron of any desired shape in cross-section, and consists, principally, of the upright 30 portion B', the lower end of which is preferably tapered or shouldered, screw-threaded, as at B², and passed through an aperture in the bolster, where it is provided with a binding-nut, B³, for the purpose of securely fastening said upright upon the bolster. The 35 upper end of the upright B is bent at a right angle to the straight portion B', as at B⁴, and forms a head, B⁵, apertured, as at B⁶.

Secured to the outer side of the upright B, by 40 rivets or other securing devices, C, is an inclined bracket or brace, C, formed with a vertical portion, C², and a knee, C³, apertured, as at C⁴, which aperture is arranged to register with the aperture B⁶ in the head B⁵. 45 The bracket C, after forming the knee C³, is extended down to the end of the bolster A, where it is apertured, as at C⁵, for the passage of a screw or other fastening device, thus forming a rigid brace for the upright B, and 50 preventing any lateral working thereof.

In Fig. 1 I have shown an additional brace or angle-iron, D, which, though not essential, adds greatly to the rigidity of the upright. This brace may be secured by bolts or rivets D' D² to the upright and bolster.

E represents a bar, stake, or pin, which may or may not, as desired, be constructed of iron, which is usually employed for the purpose of forming an upward extension to the standards or uprights in the class of wagons referred to. 55 The pin E is adapted to be passed through the aperture B⁶, the body thereof being formed to coincide with the bore of said aperture. Near its lower end is formed a shoulder, E', which rests upon the bracket-knee C³, the 60 lower end of said pin being contracted and adapted to fit within the aperture C⁴, which is somewhat smaller than the aperture B⁶.

Referring to Fig. 3, which represents a modification of my invention, it will be seen that 70 I construct the entire upright and its brace of a single piece. The deviation from the form before described will be readily apparent, in that the bar, instead of ending abruptly, as previously described, is bent upon itself, 75 and extends along down the outer side of the standard or upright for nearly half its length, where it is bent at a right angle, forming the knee C³, and is then carried down to be secured to the end of the bolster. It is also 80 apparent that said end may be either apertured, as at C⁵, and secured by means of screws to the bolster, or it may be formed with a screw-threaded end, C⁵, and passed through the bolster and secured thereto by a nut. 85

By the above construction it will be seen that I form a rigid upright, which, while more durable than those heretofore employed, prevents the usual disagreeable rattling, and also greatly strengthens and braces the bolster of 90 the wagon.

Having described my invention and its operation, what I claim is—

1. The upright B, provided with the apertured head B⁵ and the apertured bracket C, 95 substantially as specified.

2. The combination, with a bolster of a wagon having the upright B, formed with the head B⁵, apertured, as at B⁶, and the bracket C, formed with the knee portion C³, apertured, as 100

at C⁴, of the bar or pin E, formed with the shoulder E', substantially as specified.

3. The upright B, formed of a single piece of metal, and having the tapered or shouldered screw-threaded lower end, B², and the apertured head B³, and the brace C, substantially as specified.

In testimony whereof I affix my signature in presence of two witnesses.

JOHN M. DEITZ.
